STERILE BRUSH DISPENSER

Joseph Petrecca, Bloomfield, N. J.

Original application April 14, 1950, Serial No. 155,834. Divided and this application November 13, 1950, Serial No. 195,358

1 Claim. (Cl. 312—70)

1 This invention relates to a brush container and dispenser especially adapted for use in dispensing sterilized brushes that are especially useful in hospitals or other places where such devices should be used.

This present application is a continuation in greater part of my application S. N. 155,834, filed April 14, 1950, now abandoned.

In the present day practice, before performing any operation a surgeon or nurse should clean their hands with brushes that have been thoroughly sterilized. Brushes for this purpose are usually of a small size which have been substantially standardized and the practice is to put a plurality of these, usually a dozen in a dispensing container after the brushes have been sterilized. It is one of the objects of my invention to provide a casing preferably of suitable metal such as Monel or stainless steel or other rust proof types of material, whereby the brushes can be inserted into the casing and the whole assembly sterilized as a unit. It is another object of my invention to provide a casing in which the sterilized brushes can be easily and quickly dispensed without the bristles of the brush coming into contact with the hand of the user or any receptacle into which the brush may be dropped, it being understood that the receptacle used has been previously sterilized.

A further object is to provide a dispenser which is completely sealed so that no contaminated material can enter the casing while there are any brushes in it. A still further object of my invention is to provide a casing for the purposes described, which is relatively simple and inexpensive to manufacture yet one in which the brushes may be very easily and quickly extracted.

These and other objects will appear to one familiar with these structures from the reading of the specification which follows, wherein:

Figure 1 is a perspective view of one form of my invention showing the dispenser released from a support means;

Figure 2 is a perspective view of the dispenser of Figure 1 in full open position without any brushes;

Figure 3 is a view showing the bottom portions of the two sides of the casing of Figure 2 about on the line 3—3;

Figure 4 is a front view of a modified form of dispenser with the filling door open as well as the brush dispensing door, 11 brushes being indicated in broken lines;

Figure 5 is a section on the line 5—5 of Figure 4;

2 Figure 6 is a view of the lower part of another structure with a portion of the filling cover being shown and the discharge cover in open position;

Figure 7 is a section on Figure 6 similar to Figure 3;

Figure 8 is a section on line 8—8 of Figure 7;

Figure 9 is a side elevation of a brush guide means, which may be used instead of the forms shown in Figures 6 and 7;

Figure 10 is a view of the lower part of Figure 7 taken from the opposite side with a part of the casing broken away to show additional means for simultaneously opening the cover and releasing a brush;

Figure 11 is a bottom end view of Figure 10 with the cover in open position;

Figure 12 is a side view of the parts shown in Figure 10 on the line 12—12 of Figure 10.

In the different views wherein like numbers refer to corresponding parts 1 is a casing having a filling door 2 hinged at 3 and 4 to a side 5 of the casing. This side 5 has fastened thereto as by rivets or spot welding a pair of mounting clips 6 and 7 which have fingers for slipping into brackets 8 and 9 preferably punched outwardly from a mounting strip 10 adapted to be fastened to some support member by screws going through holes 11 in the strip 10.

Hinged to the bottom of the casing, preferably to the side 5 is a bottom or dispensing cover 12 which has side flanges 13 and one end flange 14 to fit closely over the lower edges of the casing as shown in Figure 1. It will be noted that the lower portions 15 and 16 of the casing extend beyond a cross brace 17 and are embraced by the flanges of the cover 12 and the cross brace 17 is also overlapped by the flange 13. The lower part of the rear wall of the casing has a cut out section 18, the purpose of which will be later explained.

Fastened to the inside of the side wall 5 as by a screw or rivet 19 is a guide member 20 having an inwardly offset 21 that acts on the handle portion 22 of a brush to push the brush over towards the opposite side of the casing. Back of the guide member 20 is positioned a resilient member 23 which may be held in place by one of the rivets that helps to hold the clip 7 in place. The guide member 20 has an inturned lip 24 having a notch therein to let the end of

spring member 23 protrude to a point adjacent the inturned ledge 25 (see Figure 2) which serves to catch one end of the brush handle while the spring 23 pushes the brush so its opposite end will be sure to rest on the ledge 26. It is to be under-

stood that the casing is filled by passing the brushes through the opening provided at the top of the casing as defined by cut away portions 27 and 28 in the side guide flanges 29 and 30.

To remove a brush from the dispenser, the bottom door is pulled downwardly to cause the hole or recess 31 in the flange 14 to leave the boss 32 in the side wall of the casing. After the door 12 is moved to the position as shown in Figures 2 and 3 the handle portion 22 of which is of wood or suitable plastic is seized between the fingers and thumb of one hand of the operator with the palm up and the handle pushed to the left looking at Figure 3 against spring 23 until the opposite end of the brush leaves the ledge 26 when the brush with the aid of spring 23 may be easily and quickly removed. It is to be noted that the width of the cut out section 18 is about the thickness of the handle of the brush and thereby makes room for the fingers of the operator to grasp the side of the brush handle. As soon as the lower brush is removed the spring 23 moves immediately inwardly and engages a downcoming brush and pushing it into the position for removal as has been described and if only one brush is desired, then the cover 12 is moved to closed position.

It may be noted in passing that the loading door may be held in closed position by a clip 33 having a recess to engage a boss 34 on the side of the box as shown in Figure 2. Also this same side has a holder plate 35 held in place by a lip 54 engaging the edges of a slot in the casing and a screw 36. The plate 35 carries a transparent member 37 which may be of glass to show when the brushes in the dispenser are getting toward the end of the stack which usually is ten or twelve brushes.

In the form shown in Figure 4 the plate 38 of the casing has fastened thereto in any satisfactory manner, a pair of oppositely disposed guide spring members 39 and 40 having an offset similar to 21 of spring 29, Figure 3, and each has a finger 41 (see Figure 5) engaging the plate 38 opposite the door 2, to approximately fix the movement of the springs toward the plate 38. Also each of the springs 39 and 40 has a cut out portion 42, spaced one from the other, a little more than the length of the brush handle. For co-operation with cut out portions 42 the plate 38 has a cut away part 43. The sides of the casing at their lower ends have ledges 44 and 45 which receive the handle of each brush as it drops down. When the bottom cover 12 is moved to open position, the brush handle may be grasped and the brushes slide out on the ledges 44 and 45 through the cut away portion 43 in the wall 38.

In Figures 6, 7, 8, and 9, the brushes are delivered from the dispenser by a different action of parts. In these figures a member 46 is pivoted at 47 between the plate 38 and the flange 29 and an operating lever 48 is attached to one of the pivot studs or the studs may be integral with member 46. The bottom part of member 46 has an offset portion 49 which is engaged by a spring 50 that is positioned against the side of the casing to which the mounting members 6 and 7 are attached. The upper part of member 46 carries a roller 51 which as shown in Figure 7, is located, due to the action of spring 50, below the end of the guide member 52 and closer to the side of the casing than the inner edge 52' of the guide member 52, which may be a channel shaped member extending from just above the roller 51 to a point near the top of the casing or the guide member

may be much shorter and of a different form as shown in Figure 9.

In the forms shown in Figures 6-9 wherein a member similar to 46 is used along with an operating lever, either the side 5 of the casing will require a recess therein to receive member 46 or else the casing will need to be a little wider to carry it in proper position to handle the brushes and this extra width must be taken up by a guide member to hold the brushes in operative alignment. This is done in Figures 6 and 7 by using a relatively long channel piece 52 which may have a depth such that the web of the channel is substantially in line with the inner edge of flange 29, depending of course, on the width of this flange.

I prefer for this wider casing the channel type guide member 52 over the shorter guide member 54 shown in Figure 9 wherein the member 54 is similar to member 29 of Figure 3 except no spring like 23 is required.

Also an assistant stop member in the form of a pin 53 is located between the plate 38 and the side flange 30.

In this form the handle of the lower brush normally rests against the pin 53 and the offset in the pivoted member 46. To extract a brush from the dispenser the bottom cover 12 is opened and the handle 48 moved downwardly and the bottom brush will be moved into a suitable receptacle or a hand of the operator (see Figure 7). The movement of the member 46 by its lever 48 will at the same time move the roller 51 inwardly into the path of a downcoming brush and at the same time the opposite end of the brush handle will be moved to engage the stop pin 53.

In Figures 10, 11 and 12 I have shown an improved form of the structure shown in Figure 7 in that the cover 12 below the brushes, is hinged at 58 along one side of the casing instead of on an edge as in the other figures.

Fastened to the inside wall of the cover 12 is a device or bent finger 57 under which projects the bent end of an arm 55 that is operatively connected to the lever 48. As shown, the arm 55 is of round material and preferably when so made, has its end 56 flattened or ground off and slightly curved upwardly as shown in Figure 10 so in operation, the end of the arm will not get blocked on the bottom of the side wall of the casing.

With this construction the cover and arm 55 are operated by the lever 48 at the same time that the bottom brush is released. Other than the additions above described, the construction is the same as in Figure 7 and its associated figures.

From what has been said it will be seen that many of the details may be varied without departing from the spirit of my invention and the scope of the appended claim.

Having thus described my invention, what I claim is:

A sterile brush dispenser for the type of brush described, including a casing preferably of suitable metal and having internal dimensions to properly hold a plurality of brushes in stacked relation on supports at the bottom of the casing with the backs of the brushes towards said supports and exit end of the casing, means for supporting the casing, means associated with the casing for allowing brushes to be placed therewithin, a fixed stop member for one end of the bottom brush, a member pivoted near the bottom of the side of the casing opposite to said fixed stop and having a stop portion normally extending downwardly and inwardly into the path of the

downward movement of the brushes, said pivoted member having an upwardly extending part preferably carrying a roller normally out of the downward path of movement of a brush, a lever for moving the pivoted member so as to cause said stop portion to move out of the path of the bottom brush and cause it to drop downwardly at the same time moving the part carrying the roller into a stop position for the next downcoming brush, a cover hinged to the casing below the brushes and having an operating device attached thereto and means operatively connected between the lever and cover device for moving the cover to open position co-incident with the release of a brush whereby the bottom brush may be passed to a proper receptacle, and further defined in that when said lever is released from cover opening and brush releasing position, automatic means will act on said pivoted member, said lever and

arm to restore them to normal position whereby a brush is moved to an unloading position onto said stops and the cover to closed position.

JOSEPH PETRECCA.
